US00D606017S

(12) **United States Design Patent**
Charlson et al.

(10) **Patent No.:** US D606,017 S
(45) **Date of Patent:** ** Dec. 15, 2009

(54) **CONVECTION COOLED FREQUENCY CONVERTER**

(75) Inventors: **Simon Charlson**, Manchester (GB);
Lyndon Shenton, Newcastle-Under-Lyme (GB); **Jürgen Wagner**, Stein (DE)

(73) Assignee: **Siemens Aktiengesellschaft**, München (DE)

(**) Term: **14 Years**

(21) Appl. No.: **29/277,307**

(22) Filed: **Feb. 21, 2007**

(30) **Foreign Application Priority Data**

Aug. 21, 2006 (EM) 000585112

(51) **LOC (9) Cl.** 13-02

(52) **U.S. Cl.** D13/110

(57) **CLAIM**

The ornamental design for a convection cooled frequency converter, as shown and described.

DESCRIPTION

FIG. 1 is a front elevation view of a convection cooled frequency converter showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view thereof.

The broken lines shown represent unclaimed subject matter and form no part of the claimed design.

The SIEMENS name forming part of the claimed design is a registered trademark of Siemens Aktiengesellschaft Company.
